UNITED STATES PATENT OFFICE

GEORGE WORDINGHAM, OF MILWAUKEE, WISCONSIN

SOFT-COLLAR CASE

Application filed February 20, 1929. Serial No. 341,503.

This invention relates to special receptacles and more particularly to a container or case in which soft collars are to be placed after being laundered and returned to the customer in the case.

One object of the invention is to provide a container or case of this character formed of stiff cardboard and so constructed that collars may be very easily placed therein in a flattened condition and not only prevented from being soiled but also prevented from becoming crumpled.

Another object of the invention is to allow side walls of the container to be releasably connected at their ends and free sides and prevent collars from slipping out of the container.

Another object of the invention is to form the container from a sheet of cardboard of such shape that a number may be cut from large sheets or strips of cardboard without waste and thereby allow the container to be very cheaply produced.

Another object of the invention is to so form the case or container that side walls of the same will be joined by a transversely curved portion having sufficient stiffness to retain its shape and allow a number of collars to be placed in the container and the container closed without danger of crumpling the collars.

The invention is illustrated in the accompanying drawing, wherein

Figure 1 is a view showing the container closed in enveloping relation to a collar, a portion of one wall of the container being broken away,

Fig. 2 is a longitudinal sectional view through the case or container taken on the line 2-2 of Fig. 1,

Fig. 3 is a view of the blank from which the container is formed, and

Fig. 4 is a transverse sectional view through the container taken on the line 4-4 of Fig. 1 with the collar omitted.

The improved collar case is formed from a sheet of cardboard, such as shown in Fig. 3 and indicated in general by the numeral 1, and this sheet is preferably oblong in shape so that it may be cut from a large sheet or

long strip without waste. A longitudinally extending slit 2 is formed adjacent one side edge of the sheet intermediate its length and in opposed relation to the slit the other side edge portion of the sheet is cut to form a tongue 3 which tapers towards its free end. Slits 4 are formed in the end portions of the sheet in the side portion thereof having the slit 2 formed therein and the other side portion of the sheet is cut from its ends to form tongues 5 which also taper toward their free ends and are adapted to be passed through the slits 4 when the case is in use. After the sheet or blank 1 has been cut to form the slits and tongues its intermediate portion between the longitudinally extending dotted lines 6 is steamed until it is soft enough to be easily folded without cracking and the sheet is then folded about a form and secured until it has dried and the temporarily softened portion again hardened. If so desired, it may be ironed or baked while drying. When the temporarily softened portion of the sheet has again hardened, the sheet will remain in its folded condition thereby providing a container having side walls 7 and 8 joined by a transversely curved portion 9 having sufficient stiffness to retain its arcuate shape, as shown in Fig. 4, while at the same time allowing the side walls to be moved toward and away from each other. Therefore, the side walls may be separated in order to open the case and place one or more collars into the case. The fact that the connecting portion 9 is curved transversely will allow a number of collars to be placed therein and the walls moved toward each other to a closed position without danger of edge portions of the collars becoming bent and the collars crumpled.

When the container is in use, a soft collar, such as shown in Fig. 1 and indicated by the numeral 10, may be placed in the case between its side walls and the tongues 3 and 5 passed through the slits 2 and 4. Therefore, the side walls will be securely joined at their ends and intermediate their length and there will be no danger of them accidentally becoming released. In view of the fact that the tongues taper toward their free ends, they

can be very easily passed through the slits. It should be noted that by having the end tongues and slits located intermediate the side edges of the walls these tongues will be located opposite the outer ply or portion of a turndown collar placed in the case in a flattened condition and the end portions of the inner ply having buttonholes formed therein will be disposed between the tongues and unite inner side edge portions of the walls of the container. By this arrangement the collar will be prevented from sliding longitudinally out of the case or container and there will be no danger of a collar becoming lost or soiled before it is delivered to a customer. Advertising matter and the name of a laundry may be printed or otherwise applied to the outer faces of the walls and also there may be provided space for the name and address of the customer upon one wall.

Having thus described the invention, I claim:

A container comprising a sheet of material folded to form walls of substantially equal dimensions disposed one in covering relation to the other and integrally united thereto along one side of the container, the end edges and other side edges of the walls being free whereby a collar may be placed in a flattened condition between the walls with the free marginal portions of the walls projecting beyond its ends and beyond the outer longitudinal edge of the collar, the free marginal portions of one wall having slits formed therein intermediate the length of its longitudinal edge and intermediate the length of its end edges and corresponding portions of the other wall being provided with tongues engageable through the slits to releasably hold the said marginal portions of the walls in close relation to each other beyond the collar and provide a stop intermediate the length of a collar and other stops opposite ends of the collar intermediate the depth thereof and serving to retain the collar in place within the container.

In testimony whereof I affix my signature.
GEORGE WORDINGHAM. [L. S.]
